DESIGN FOR A GAME BOARD

William P. Ulrich, Spokane, Wash.

Application April 12, 1941, Serial No. 100,350

Term of patent 14 years

To all whom it may concern:

Be it known that I, William P. Ulrich, a citizen of the United States, residing at Spokane, in the county of Spokane and State of Washington, have invented a new, original, and ornamental Design for Game Boards, of which the following is a specification, reference being had to the accompanying drawing, forming part thereof.

I claim:

The ornamental design for a game board, as shown.

WILLIAM P. ULRICH.
